LEWIS J. CLAPP, OF CLAREMONT, NEW HAMPSHIRE, ASSIGNOR TO SULLIVAN
MACHINERY COMPANY, A CORPORATION OF MASSACHUSETTS

COMPRESSOR CONTROLLING MECHANISM

Application filed March 28, 1930. Serial No. 439,598.

This invention relates to means for controlling prime movers and compressors or pumping equipment and relates more particularly to an improved combination for controlling the loading or unloading of a compressor and also controlling the prime mover which actuates the compressor. Various systems and arrangements have heretofore been proposed for effecting coordinated control of the prime mover, such as an internal combustion engine, and a compressor driven thereby, but such systems and arrangements have certain objections either in being complicated or lacking stability in effecting control, or in being relatively expensive to manufacture and maintain, other difficulties also being present, as is understood to those skilled in the art. An object of my invention is to provide an improved arrangement for effecting coordinated control between the prime mover and the compressor. A further object is to provide an improved arrangement for controlling the speed of the prime mover and for effecting loading or unloading of the compressor. Another object is to provide an improved simplified arrangement for controlling the speed of an internal combustion engine and for controlling the loading and/or unloading of the compressor. A further and more specific object of the invention is to provide an improved arrangement and means whereby the speed of the prime mover may be controlled independently of the unloading mechanism when the compressor is in its loaded condition. Another specific object of the invention is to provide an improved arrangement and means which will be relatively simple yet will have a high degree of stability of control and may be easily maintained in operation and will be relatively inexpensive to manufacture. Other objects and advantages of my improved invention will be readily understood by those skilled in the art and will be more fully understood from the following description and the accompanying drawings.

In these drawings I have shown for purposes of illustration one embodiment that my

This invention may assume in practice. In the drawings, Fig. 1 is a side elevation of a portable compressor embodying my improved arrangement. Fig. 2 is an enlarged fragmentary side elevation of the prime mover and control elements associated therewith. Fig. 3 is an enlarged sectional view of the controlling mechanism adapted to cooperate with the throttle valve of the prime mover and to be actuated by the pressure fluid in the receiver. Fig. 4 is an enlarged fragmentary section of the right end of the prime mover speed governor. Fig. 5 is an enlarged sectional view of the valve mechanism of the controlling mechanism shown in Fig. 3. Fig. 6 is an enlarged fragmentary section of the engine throttle valve and operating lever. While I have shown the illustrative embodiment of the invention in connection with a portable compressor, it will of course be understood that the invention is applicable to any prime mover-compressor arrangement irrespective of the manner in which it may be supported. In any case, there is a prime mover, generally indicated at 1, herein preferably of the internal combustion engine type, and compressor 2, suitably connected for drive to the crank shaft of the engine, and of the reciprocating piston and cylinder type having usual inlet and exhaust valve mechanisms. Preferably the inlet valve mechanisms are provided with any usual form of fluid operated unloading mechanism, generally indicated at 3, and adapted to unload the compressor when fluid pressure in the receiver 4 reaches a predetermined value. Fluid from the receiver is conducted through a pipe 5 to any usual type of pilot valve mechanism 6, and then to a pipe 7 leading to one end of a control mechanism, generally indicated at 8. This mechanism is adapted to control the engine throttle valve 9 in a manner which is well understood in the art, its specific form being disclosed in the Holdsworth Patents 1,692,267 and 1,785,956. In

50 100

view of these disclosures, a detailed description of the valve mechanism will not be given, it being sufficient to state here that when the pilot valve 6 admits fluid pressure to the pipe 7, as upon receiver pressure reaching the predetermined maximum value, a piston 10 moves a stem 11 and nose 12 against the engine throttle valve lever 13 to close the same and at the same time fluid continues through a U-shaped pipe 14 to a valve mechanism, generally indicated at 15, thereby to force the movable valve 16 open and permit pressure fluid to flow through a pipe 17 to the unloading mechanisms 3 and thereby unload the compressor. When the unloading function is accomplished, flow through pipe 17 will cease thus permitting pressure to be equalized on each side of the valve 16 whereupon a spring 18 will then close this valve to cause the stem 19 to project into the cylinder for piston 10. When receiver pressure drops to a predetermined minimum and the pilot valve vents the pipe 7, a spring 20 will move piston 10 to the right and abut against and move the stem 19 and valve 16 to open position, thereby likewise venting the pipe 17 and unloading mechanisms 3 through the pipes 14 and 7, thus causing the compressor to be reloaded. From this it will be clear that venting of the air that acts in the devices 3 to effect unloading will not occur until the nose 12 has ceased to hold the lever 13 in the position to which it moved it when air acted on piston 10.

35. As shown in Fig. 2, the nose 12 of the controlling mechanism merely abuts against the throttle valve lever of the prime mover and is in substantially opposed relation to an operating link 21 which is pivotally connected at one end to the throttle lever 13 and at its other end to a speed governor operating lever 22 which is its full open position in Fig. 2. This speed governor, for operating lever 22, is of a usual and well-known type, driven preferably, and as herein shown, directly by the usual timing gears for the engine valve mechanism, which timing gears are contained within the usual gear case 24. The governor is of the centrifugally actuated type having a stem 25 movable to the right (Fig. 4) upon an increase in speed and in the opposite direction upon a decrease in speed, there being a lever 26 herein held in abutting engagement with the rod 25 as by an adjustable spring 50 pressed rod 27. The lever 26 is pinned to the pivotal shaft 28 to which the lever 22 is likewise secured. While a compression spring 29 is shown it will of course be understood that any spring arrangement may be employed which will hold the lever 26 in engagement with the speed responsive pin 25.

55. From the foregoing description of the compressor prime mover controlling mechanism 8 and the description of the speed responsive governor mechanism 23 it will be

readily seen that both devices operate directly upon the single throttle valve which controls the supply of fuel from a usual carburetor to the engine cylinders and thus controls the speed of the engine in the usual and well-known manner, and, due to the spring arrangement for holding the levers 26 and 22, the fluid actuated control mechanism 8 is adapted to move the throttle valve automatically in accordance with the receiver pressure so as to unload the compressor and control the speed of the engine without in any way encountering any opposing force from the speed responsive element of the speed governor such as may be created by the centrifugal force therein. It is also seen as previously pointed out that the speed governor may close the throttle valve independently of the controlling mechanism 8 and yet the speed governor and controlling mechanisms are adapted to be maintained simultaneously in cooperating relation with the single throttle valve during normal operation.

It is thus seen that my arrangement is relatively simple both in structure and operation, requiring relatively few parts and only a single engine throttle valve, and while the various controls are shown as applied to a throttle valve of an internal combustion engine, it will of course be understood that this throttle valve comprises broadly a power medium control for a prime mover which may be of any usual form for driving pumping mechanisms such as compressors.

While there is in this application specifically described one form which the invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. The combination with a compressor and a prime mover for driving the same, of means for controlling the prime mover including a power medium control element therefor, means for controlling said element in accordance with the speed of the prime mover, and means governed by the compressor discharge pressure for controlling said element directly to slow down said prime mover when the compressor discharge pressure exceeds a predetermined desired maximum, each of said means having operative connection with the element whereby their respective operating forces are applied to the element substantially in a common plane.

2. The combination with a prime mover operated compressor, of a power medium control element for said prime mover, a pivoted member for actuating said element, means operatively connected to said member for

controlling said element in accordance with the prime mover speed, and means also separately operatively connected to said member for controlling said element in accordance with the compressor discharge pressure, the operative connection of each of said means with said pivoted member being on the same side of its pivot.

3. The combination in a prime mover operated compressor comprising a power medium control element, means for controlling said element in accordance with the speed of said prime mover including a yieldably held member normally moved in accordance with the prime mover speed, said member being operatively connected to said power control element, and means for also controlling said element in accordance with an operating condition of said compressor and adapted upon operation to cause directly yielding of said speed responsive member.

4. The combination of a prime mover operated compressor, comprising a power medium control element for said prime mover, means for controlling said power element in accordance with the speed of the prime mover, and means for also controlling said power element in accordance with an operating condition of said compressor, each of said means having an operative connection with said power element operative directly to reduce the flow of power medium to the prime mover.

5. The combination set forth in claim 4 further characterized in that operative connection between the power medium control element and speed responsive means is positively connected to the power medium control element.

40 6. The combination set forth in claim 4 further characterized in that the operative connection between the power medium control element and speed responsive means has provision for moving the power medium control element in opposite directions.

45 7. The combination in a compressor driven by an internal combustion engine having a pivoted throttle valve and an operating lever therefor, comprising means for controlling said valve in accordance with the speed of said engine, and means for controlling said valve by fluid pressure, each of said means having an operative connection with said valve lever and at least one of said connections being adapted to effect movement of the lever in opposite directions.

8. The combination with a compressor driven by an internal combustion engine having a pivoted power medium control valve and an operating lever, of means for controlling said valve in accordance with the speed of said engine, and means for controlling said valve by fluid pressure, each of said means having an operative connection with said valve lever on the same side of the pivot thereof and

when effective moving it in the same direction.

9. In combination, a compressor having fluid pressure operated unloading mechanism, an internal combustion engine for driving said compressor, a receiver into which the compressor discharges, means including a pilot valve for controlling the loading or unloading of said compressor in accordance with the receiver pressure, means for controlling the speed of said prime mover in accordance with the speed thereof and in cooperation with the means for controlling the loading of the compressor, said speed control including a yieldable connection adapted at least under certain conditions of operation to yield under the influence of the compressor controlling mechanism.

10. In combination, a compressor having fluid pressure operated unloading mechanism, an internal combustion engine for driving said compressor, a receiver into which the compressor discharges, means including a pilot valve for controlling the loading or unloading of said compressor in accordance with the receiver pressure, a throttle valve for controlling the flow of power medium to said engine, means whereby said compressor load controlling means is operatively connected to said valve for effecting closure thereof at a time when the compressor is unloaded, and speed responsive means for also controlling said valve in accordance with the speed of said prime mover including a yieldable connection between the throttle valve and speed responsive means.

In testimony whereof I affix my signature.
LEWIS J. CLAPP.
